NOTEBOOK LOOSE-LEAF BINDER

Samuel Segal, New York, N. Y., assignor to Wilson-Jones Company, Chicago, Ill., a corporation of Massachusetts

Application March 25, 1947, Serial No. 736,969

5 Claims. (Cl. 129—24)

1

This invention relates to an improved and simplified loose leaf binder particularly applicable to pocket notebooks and of the type having an oscillatable stay on which a stack of sheets may be desirably and removably threaded on spaced prongs thereof. Broadly, one important object of the invention resides in the provision of a strap or band appropriately secured to a cover of the notebook and having bearing means for slidably and rotatably guiding an arched axle of the stay or prong carrier and embodying inclined keeper means spaced from the bearing means but disposed longitudinally thereof for interlocking with and frictionally maintaining the prongs of the stay fully transversely across the strap, that is, desirably closed and against rotation transversely of the strap. Another object of the invention is to provide means struck out of the keeper and disengageably cooperating or locking with one of the prongs of the stay to resist linear bodily displacement of the latter. Another object of the invention is realized in the provision of a one piece relatively flat strap disposed widthwise of the cover and comprising upstanding but inclined keeper means integral with and arranged longitudinally of the anterior portion of the strap and provided with spaced relief indentations for removably alining or registering with the anterior free terminals of downwardly and forwardly inclined rectilinear portions of the prongs of the stay to permit bodily rotation of the spaced prongs upwardly and rearwardly away from the biased or inclined keeper means and in a direction towards the bearing means in the matter of opening the loose leaf binder. Specifically another object of the invention is concerned with the provision of bearing means integral with the relatively elongated body of and arranged on the posterior part of the strap for rotatably and slidably guiding the axle of a one piece wire stay having upstanding, inverted and substantially U-shaped and spaced prongs provided with inclined or biased rectilinear portions removably adapted to be in alinement with correspondingly spaced relief indents interrupting the anterior keeper means and adapted to disengageably but frictionally cooperate with the overlapping and tilted keeper means to hold the stay closed and against accidental opening. Other functional and structural features and advantages will be apparent from the following detailed description taken with the teachings of the accompanying drawings wherein:

Fig. 1 is a fragmentary perspective view of the notebook illustrating the loose leaf binder ac-

2

cording to my invention closed and locked, and held against accidental opening.

Fig. 2 is a plan view of Fig. 1.

Fig. 3 is a front elevational view of Fig. 2.

Fig. 4 is an end view on the line 4—4 of Fig. 3, showing one of the prong means of the stay in frictional and tight interlocking engagement with the upstanding but biased or inclined keeper means of the strap.

Fig. 4A is a perspective view of the one piece wire stay.

Fig. 5 is a view similar to Fig. 1 but showing the rotatably and slidably guided stay closed but unlocked in which case the prongs are in registration with the spaced indents of the biased or tilted rectilinear anterior keeper.

Fig. 6 is a transverse sectional view on the line 6—6 of Fig. 5.

Fig. 7 is a view similar to Fig. 5 however exhibiting the rotatable and slide stay of the loose leaf binder raised to a fully opened position.

Fig. 8 is an end view of Fig. 7.

Fig. 9 is a view along the lines of Fig. 1 but illustrating a reinforced inclined keeper embodying ancillary or supplementary means to preclude slide or linear displacement of the stay, and

Fig. 10 is a transverse sectional view on the line 10—10 of Fig. 9.

Referring now to the drawings and particularly to Figs. 1—8 the loose leaf binder generally designated LL constructed in accordance with my invention is constituted by a relatively flat and narrow sheet metal relatively elongated strap or band 10 disposed widthwise and preferably arranged at the front end of the stack supporting sheet 11 of the memorandum or note book broadly indicated 12 (Fig. 1) having the swingable interenor 13 merged with the swingable closure sheet 14. Sheets 11 and 14 together with the interenor 13 characterize an appropriate one piece cover for the block or stack of perforated paper or sheet material 15 shown in dash and dot lines. As is well appreciated the cover is flexible and may be of a suitable card board, leather, imitation leather or of a plastic composition. More particularly, strap 10 is secured against displacement by the primary fastening means, namely the downwardly and inwardly bent lips 16 integral with the body of the strap and by the supplementary or ancillary fastening means in the form of spaced detents or projections 17 struck out of the body of the metal strap.

Integral with the posterior or back margin of the strap and arranged longitudinally and sub-

55

stantially centrally or medially thereof is the hollow cylindrical bead or bearing 18 rotatably and slidably guiding the cylindrical axle 19 of the one piece wire stay or carrier generally indicated 20 embodying the upstanding inverted substantially U-shaped prongs 21 each provided with a downwardly and forwardly sloping or inclined and rectilinear portion 22 all adapted to be removably alined or register with spaced grooves 23 of the outwardly directed indents or sockets 24 interrupting the upstanding and inclined or biased rectilinear flange or keeper means 25 integral with the body of the strap 10 which straddles sheet 11. The keeper means 25 leans rearwardly towards the body of the strap to define an acute angle therewith.

The elbows 26 and 27 at the confluence of the transversely disposed prongs 21 and longitudinally arranged but arched or bowed axle 19 of the one piece wire rotatable and slidable stay 20 coat with the ends or stop means 28 and 29 of the bearing 18 to limit linear displacement of the stay and when elbow 26 strikes the stop or end 28 (Fig. 5) the biased or inclined fingers or terminals 22 are in alinement with the relief grooves 23 of the indents or sockets 24.

By such action the prongs 21 of the stay are unlocked or disengaged from the keeper means or rectilinear flange 25. Consequently the stay may be bodily rotated to permit swingable displacement of the prongs 21 upwardly and rearwardly from their fully closed but unlocked position illustrated in Fig. 5 to their fully opened and removed position shown in Fig. 7.

With the stay fully opened, the perforated stack of sheet material or block of papers 15 as is well understood may be conveniently threaded on the inclined and now free terminals 22. Thereafter the stay may be rotated to its closed position (Fig. 5) whereby forwardly and downwardly sloping terminals again are in close alinement with the spaced grooves. Subsequently, the stay is bodily and slidably shifted to move elbow 26 away from the bearing whereby elbow 27 moves towards and against stop 29 at which time the terminals of the inclined portions 22 of the prongs not only frictionally, wedgeably and removably engage inclined face 29' of the tilted keeper 24 but in addition the latter prevents opening of the prongs, that is, their accidental swinging or rotation upwardly and away from the keeper. Furthermore in the closed and frictional engagement of the terminals of the sloping portions 22 and the lower part of keeper 25 as shown, these elements may be considered as interlocked in that they overlap as shown in Fig. 4, consequently precluding rotation of the stay away from the keeper, however permitting bodily linear displacement of the stay when manual pressure on the latter is exerted to overcome the frictional stress between the prongs and the keeper.

Of course terminals of the sloping portions 22 immediately frictionally engage the inclined face 29' of the keeper after linearly passing by the grooves 23 when the stay is shifted and such action is retained by the camming action of the arched or bowed axle 19 on the bearing 18, there being ample clearance as is well understood in the bore of the bearing to permit such camming. The prongs 21 comprise; upstanding limbs rising vertically from elbows 26 and 27 and substantially normal to the axle 19, the rectilinear bridge portions integral with the upstanding limbs and substantially parallel to the body of the strap 10 when the stay is in a closed relation (Fig. 4),

and the depending rectilinear sloping portions 22 integral with and forming obtuse angles with the bridge portions. In the closed relation of the stay the acute angles formed by inclined portions 22 and the body of the strap 10 are less in divergence than the acute angle between flange 25 and strap 10. For purposes of exact determination and as previously mentioned the spaced prongs are identified by numerals 21 and in Figs. 1 and 10 4A these numerals have their lead lines on the aforementioned intervening or intermediate bridge portions which merge with and are substantially normal to the straight limbs rising from the above elbows 26 and 27. By the present and simplified arrangement it is apparent that a more sturdy construction against undesirable deformation of the prongs 21 is provided permitting the rectilinear bridge portions to effectively absorb the reactive thrust applied to the anterior and inclined portions 22 when wedgeably engaging the inclined abutment flange 25.

In the form according to Figs. 9 and 10 the keeper is provided with an outwardly and downwardly turned juxtaposed web 30 for reinforcing purposes. It will also be observed that a 25 dimple or projection 31 is struck out of the keeper 25 adjacent one of the indents 24. The projection 31 serves to removably interlock with one terminal of the sloping portions 22 to resist accidental 30 slidable displacement of the stay. Thus in Figs. 9 and 10 to slidably unlock the stay the latter is linearly shifted to snap over detent or projection 31 until it aligns with the indents or sockets 24 of the keeper 25. Detent 31 in cooperating 35 with one of the prongs may be said to be supplementary or ancillary locking means to resist slidable displacement of the stay and such supplementary locking means is effective when the stay is closed and linearly shifted to snap by 40 detent 31. In other aspects the form according to Figs. 9 and 10 is along the lines of the embodiment illustrated in Figs. 1-8 inclusive and in all the forms herein disclosed, the stay is rotatably and slidably but linearly associated with the bearing 45 integrally turned upwardly and forwardly and then downwardly along the posterior portion of the body of the stay. In all of the embodiments shown and described herein the stay is disengagably and frictionally braked in a set position by 50 the rearwardly inclined or tilted keeper and such action is retained by the camming action of axle 19.

In Figs. 1 and 5, the stay is closed, although 55 sustained, locked and unlocked respectively and in such relations, the spaced prongs may be said to be fully across the width of the strap. In all of the forms disclosed, the stay 10 has its spaced prongs 21 substantially normal to the arched axle 19 and the prongs traverse the strap in the closed 60 relation of the stay at which time the keeper means 25 when braking the prongs interlock, overlap and are in frictional relation with the prongs which of course widely straddle the bearing 18 to permit linear displacement of the stay.

65 Various changes may be made in details of construction and arrangement of parts without departing from the spirit of the invention or sacrificing any of the advantages thereof inherent therein.

70 I claim:

1. A loose leaf binder; comprising, a relatively elongated strap embodying a rectilinear body having a bearing disposed along one longitudinal margin thereof, an upstanding rectilinear abutment flange biased relative to said body and de-

fining an acute angle therewith and spaced from and leaning in a direction towards said bearing and including spaced indent means, and a stay having means movably guided by said bearing and including spaced prong means embodying intermediate rectilinear bridge portions and depending rectilinear portions defining with said bridge portions obtuse angles and sloping outwardly and downwardly towards said flange and including free terminals only wedgeably coacting with said flange when said prong means are arranged fully across said strap and out of alignment with said indent means to preclude rotational displacement of said prong means upwardly and rearwardly away from said flange and said depending rectilinear portions adapted on voluntary bodily linear displacement of said stay relative to said bearing to be arranged in alignment with said indent means to permit swinging of said prong means bodily rearwardly fully clear of said indent means and flange.

2. A loose leaf binder; comprising, a relatively elongated strap embodying a rectilinear body having a bearing disposed along the posterior longitudinal margin thereof, an upstanding rectilinear flange biased relative to said body and integral and defining an acute angle therewith and projecting upwardly from the anterior longitudinal edge of said body and leaning in a direction towards said bearing and including spaced indent means, and a stay having an axle slidably and rotatably guided by said bearing and including spaced prong means embodying upstanding substantially rectilinear limbs, intermediate substantially rectilinear bridge portions substantially normal to said limbs, and integral with and depending rectilinear portions integral with and sloping outwardly and downwardly from said bridge portions towards said flange and including free terminals only wedgeably coacting with said flange when said prong means are arranged fully across said strap and out of alignment with said indent means to preclude rotational and linear displacement of said prong means relative to said flange and said rectilinear depending portions adapted on voluntary bodily linear displacement of said stay relative to said bearing to be arranged in alignment with said indent means to permit swinging of said prong means bodily rearwardly fully clear of said indent means and flange.

3. A loose leaf binder; comprising, a relatively elongated strap embodying a rectilinear body having a bearing disposed along the posterior longitudinal margin thereof, an upstanding rectilinear flange biased relative to said body and integral and defining an acute angle therewith and spaced from and leaning in a direction towards said bearing and including spaced indent means, and a stay having an axle slidably and rotatably guided by said bearing and including spaced prong means embodying upstanding limbs substantially normal to said axle, rectilinear bridge portions integral with and approximately normal to said limbs and arranged substantially parallel to said body in the closed relation of said stay relative to said strap and having depending rectilinear portions defining obtuse angles with said bridge portions and sloping outwardly and downwardly towards said flange and including free terminals only wedgeably coacting with said flange when said prong means are arranged fully across said strap and out of alignment with said indent means to preclude rotational and linear displacement of said prong means relative to said

flange and said rectilinear depending portions on voluntary bodily linear displacement of said stay relative to said bearing adapted to be shifted in alignment with said indent means to permit swinging of said prong means bodily rearwardly fully clear of said indent means and flange.

4. A loose leaf binder; comprising, a relatively elongated one piece strap embodying a rectilinear body having a bearing disposed along the posterior longitudinal margin thereof, an upstanding rectilinear flange biased relative to said body and integral and defining an acute angle therewith and extending upwardly from the anterior longitudinal edge of said body and leaning in a direction towards said bearing and including spaced indent means, a one piece wire stay having an arcuate axle slidably and rotatably guided by said bearing and including spaced prong means embodying rectilinear limbs substantially normal to said axle, rectilinear bridge portions above said flange and substantially normal to said limbs and having depending rectilinear portions defining obtuse angles with said bridge portions and in part disposed above said flange and sloping outwardly and downwardly towards said flange and including free terminals only wedgeably coacting with the lower margin only of said flange when said prong means are arranged fully across said strap and out of alignment with said indent means to preclude involuntary rotational and linear displacement of said prong means relative to said flange and said depending rectilinear portions on voluntary bodily linear displacement of said stay relative to said bearing adapted to be arranged in alignment with said indent means to permit swinging of said prong means bodily rearwardly fully clear of said indent means and flange, and detent means on said flange cooperating with at least one of said depending rectilinear portions to resist slidable displacement of said stay.

5. A loose leaf binder; comprising, a relatively elongated strap embodying a rectilinear body having a bearing disposed along the posterior longitudinal margin thereof, an upstanding rectilinear flange biased relative to said body and integral and defining an acute angle therewith and extending upwardly from the anterior longitudinal edge of said body and leaning in a direction towards said bearing and including spaced indent means, and a stay having an axle slidably and rotatably guided by said bearing and including spaced prong means embodying upstanding limbs, rectilinear bridge portions above said flange and depending rectilinear portions defining with said bridge portions obtuse angles and sloping outwardly and downwardly towards said flange and including free terminals wedgeably coacting with the lower margins only of said flange when said prong means are arranged fully across said strap and out of alignment with said indent means to preclude involuntary rotational and linear displacement of said prong means relative to said flange and said depending rectilinear portions on voluntary bodily linear displacement of said stay relative to said bearing adapted to be arranged in alignment with said indent means to permit swinging of said prong means bodily rearwardly fully clear of said indent means and flange, said depending rectilinear portions defining with said body acute angles slightly less in divergence than the acute angle formed by said body and rectilinear flange.
